UNITED STATES PATENT OFFICE.

JAMES WALTON, OF PHÖNICIA, NEW YORK.

ACETYLENE-GAS MACHINE.

SPECIFICATION forming part of Letters Patent No. 643,576, dated February 13, 1900.

Application filed June 2, 1899. Serial No. 719,127. (No model.)

To all whom it may concern:

Be it known that I, JAMES WALTON, of Phœnicia, in the county of Ulster and State of New York, have invented a new and Improved Gas-
5 Machine, of which the following is a full, clear, and exact description.

This invention relates to improvements in acetylene-gas machines; and the object is to provide a gas-machine of comparatively simple construction in which all the carbid contained in a charge will be consumed to generate gas, thus resulting in economy of production, and, further, to so construct the machine that there are no pressure-actuated
10 valves that might corrode and interfere with the perfect working of the machine, and, still further, to so arrange the parts that upon an excessive gas-pressure the excess will be quickly and automatically relieved and dis-
15 charged into the outer atmosphere or into a sewer or the like.

I will describe a gas-machine embodying my invention and then point out the novel features in the appended claims.

25 Reference is to be had to the accompanying drawing, forming a part of this specification, in which the figure of drawing is a vertical section of a gas-machine embodying the invention.

30 Referring to the drawing, 1 designates the generator-cylinder, surrounded by a jacket 2, and at the upper end of this jacket 2 is a reservoir 3 for containing water to cool the gas formed in the generator 1 and for keeping the generator cool. The top 4 of the generator is removable, but is designed to be held tightly in its closed position, as here shown, by means of a screw 5, engaging in a tapped hole in a cross-yoke 6 and impinging upon
35 the upper side of the cover. At the lower end of the generator-cylinder is an outwardly swinging bottom 7, from which a rod 8 extends downward for a purpose to be hereinafter described.

40 45 Suspended from the cover 4 is a carbid-holder 9, which is open at its top and has a perforated bottom. The carbid-holder is designed to receive the required amount of carbid to generate the desired amount of gas,
50 and obviously different sizes of holders may be employed, so that the capacity of the ma-

chine may be made to accord with the number of lights to be supplied with gas.

The generator-cylinder 1 and the parts carried thereby are movable vertically in a water-tank 10, designed to receive water, in which the carbid is to be immersed for generating gas, and also serving as a water seal and means for cooling the gas. The upper portion 11 of the water-tank is enlarged, so as to receive
55 the water pressed upward in the tank by gas-pressure on the surface of the water contained between the generator 1 and the jacket 2.

The gasometer is guided in its vertical movements by clips 12, attached to the enlarged portion of the tank 10, and in notches in which guide-strips 13 on the jacket 2 engage. The water-tank 10 has a hopper-like bottom 14, which communicates by a central port 15 with an ash-receiving chamber 16 at
60 the bottom of the tank. The port 15 is controlled by a gate-valve 17, movable in a valve-casing 18 and having a threaded-stem 19 extended outward through the side of the water-tank. The space between the lower side of
65 the hopper 14 and the top side of the upper wall of the ash-chamber 16 forms a water-chamber, in which water is to be placed to a desired height for washing, cooling, and purifying gas before it is discharged to the gasometer,
70 as will be hereinafter described. Water may be placed in this chamber through a valve-controlled pipe 19^a, and at the lower portion of the chamber there is a drain-pipe
75 80 20. A pipe 21 leads from a point near the bottom of the chamber for the purifying-water, through the funnel-shaped bottom 14, and thence between the cylinder 1 and the jacket 2, terminating at a point above the water-level in the water-tank. From the upper portion of the generating-cylinder a pipe 22 leads downward between said cylinder and the jacket, and its lower end terminates below the generator-cylinder, and it extends into the water contained in the jacket, and any foreign substance in the gas falls through the water into the ash-chamber, while the gas bubbles up through the water into the gas-chamber surrounding the carbid-receptacle.

At a point practically in vertical alinement
85 90 95 drain-pipe 23, leading downward and outward with the bolt forming the hinge for the bot-

tom 7 is located the upper end or inlet of a through the water-tank to a sewer or any other suitable place. This pipe is provided with a cock or valve 23^a to be operated when the car-
5 bid-receptacle reaches its lowermost position, in which the inlet of the drain-pipe is immedi-
ately adjacent to the bottom 7, which in such
10 position is open, as will be described herein-
after. The drain-pipe is for the purpose of
removing any water from the carbid-recepta-
cle after a charge has been exhausted, so as
15 to avoid wetting the new charge.

In connection with my generator as here-
inbefore described I employ any suitable gas-
20 ometer—for instance, the one shown in the
drawing.

Arranged at one side of the generator and
its water-tank is a gasometer having a fixed
25 portion 24 for containing water and in which
the bell 25 is vertically movable. This bell
has a conical top, and surrounding this coni-
cal top is a receptacle 26 for containing a
sand or water ballast.

A pipe 27 leads from the chamber below the
25 hopper-like bottom 14 and from a point above
the level of the water contained in said cham-
ber to the lower portion of the fixed part 24
of the gasometer, where it discharges into a
30 chamber 28 for containing cooling and puri-
fying water. This pipe 27 is provided with
suitable valves 29 and 30, and it also has a
drain-pipe 31, controlled by a suitable valve.
The upper portion of the section 24 of the
35 gasometer is enlarged, as indicated at 32, to
receive water that might be forced upward
by gas-pressure, as described in connection
with the enlarged portion 11 of the water-tank
10. From the chamber 28 a pipe 33 leads up-
ward in the gasometer and terminates at a
40 point above the water-level in the bell. An-
other pipe 34 leads downward from a point
above the water-level in the bell and connects
with the distributing-pipe 35, which leads to
the burners. A safety-pipe 36 extends up-
45 ward in the gasometer and through an open-
ing in the conical cover of the bell. At its
upper portion this pipe 36 is closed by a cap
37, and below this cap a port 38 is provided.
Attached to the cover or top of the gasometer-
50 bell and surrounding the safety-pipe 36 is a
sleeve 39, which extends nearly to the bottom
of the said bell.

In operation after a charge of carbid has
been inserted and before any gas is generated
55 the gasometer-cylinder 2 moves downward to
bring the lower end of the holder 9 into the
water, which is permitted to enter through the
bottom of the generator-cylinder, since the
closure 7 is opened by the rod 8 striking
60 against the funnel-shaped bottom 14. The
gas will immediately begin to rise and pass
in a crude state from the generator-cylinder
through the pipe 22, from which it will bub-
ble up through the water and pass to the space
65 above the water-level between the cylinder
1 and the jacket 2. This gas will then dis-
charge through the pipe 21 into the cooling and

purifying chamber, where it will bubble up
through the water, and thence pass through
the pipe 27 into the water contained in the
70 chamber 28, and thence through the pipe 33
to the gasometer-bell, and then out through
the pipes 34 and 35. When the pressure in
the generator or in the space between the cyl-
inder 1 and the jacket 2 reaches a desired
75 maximum, the holder 9 will be raised out of
the water and the generation of gas will cease
until the pressure is again reduced. Should
the pressure become excessive in the gasome-
ter, the bell will rise until its upper end strikes
80 against the cap 37 on the pipe 36, and at this
time the port 38 will be at a point within the
sleeve 39 and the lower end of said sleeve will
be above the water-level. Therefore the ex-
cessive pressure may pass out through the
85 sleeve 39 and the pipe 36, thus preventing any
possible danger of explosion by excessive pres-
sure. When the charge is spent, the genera-
tor will move downward until the rod 8 strikes
90 against the funnel-shaped bottom 14. This
will swing the bottom 7 upward, permitting
the ashes which may have collected below the
holder 9 to fall into the hopper 14, and thence
pass through the port 15 into the ash-chamber
95 16. As the ashes are much heavier than the
water they will while falling into the chamber
16 force the water upward or a greater portion
of it through the port 15. Then upon closing
the valve 17 the ashes may be removed through
100 an opening in the wall of the ash-chamber.

It is obvious that after once starting this
machine will require very little, if any, atten-
tion until the whole charge of carbid is con-
sumed. The several parts may be easily sepa-
105 rated for cleaning or other purpose, and, fur-
ther, owing to the several washings the gas
supplied to the burners will be practically
pure.

It will be observed that the bottom 7 will
normally be open, owing to the engagement of
110 the rod 8 with the bottom 14. The gas gen-
erated will normally be consumed at a suffi-
cient rate to prevent the generator 1 from ris-
ing enough to cause the bottom 7 to close. If,
however, too much gas is generated or in case
115 the delivery of gas is shut off, (as by closing
the cock 29 or 30,) the pressure within the
generator will cause the body 1 to rise, as
shown in the drawing, closing the bottom 7,
so that there will be no further supply of wa-
120 ter to generate gas. This is of particular im-
portance, as it prevents a wasteful decom-
position of carbid when the generator is not
in use.

Having thus fully described my invention,
125 I claim as new and desire to secure by Letters
Patent—

1. In a gas-machine, a water-tank, a gener-
ator-cylinder movable vertically in the water-
130 tank, a jacket surrounding and carried by
said cylinder, a carbid-holder supported in
the cylinder and having a perforated lower
end, a swinging closure for the generator-
cylinder, means for opening the closure when

the cylinder is in its lower position and a gasometer having connection with the generator, substantially as specified.

2. In a gas-machine, a water-tank, a generator-cylinder movable vertically in the water-tank, a jacket carried by and surrounding said cylinder, and having a water-receptacle at its upper end, means for supporting a carbid-holder in the cylinder, an upwardly-
10 swinging bottom for said cylinder, means for opening said bottom when the cylinder is in its lower position and pipes for conducting gas discharged from the cylinder, substantially as specified.
- 15 3. In a gas-machine, a water-tank enlarged at its upper end, a generator-cylinder movable vertically in the tank, a jacket carried by and surrounding the cylinder, a discharge-pipe leading from the upper portion of the
20 cylinder to a point near the lower end of the cylinder, another discharge-pipe for receiving gas discharged from the first-named pipe, and a water-chamber in the lower portion of the water-tank and into which the last-named
25 pipe discharges, substantially as specified.

4. In a gas-machine, a water-tank having a funnel-shaped lower portion or bottom, an ash-chamber having valve-controlled communication with said funnel-shaped bottom, a
30 water-chamber between said funnel-shaped bottom and the ash-chamber, a generator-cylinder movable in the water-tank, and means for directing gas from said generator-cylinder into the water-chamber below the funnel-
35 shaped bottom, substantially as specified.

5. In a gas-machine, a water-tank, a gener-

ator-cylinder movable vertically in the water-tank, a jacket carried by and surrounding the said cylinder, an upwardly-swinging bottom for the generator, a rod extended from said 40 swinging bottom and adapted for engagement with the bottom of the water-tank, and a receiver for receiving gas generated in the generator-cylinder, substantially as specified.

6. The combination with a water-tank, of 45 a generator movable therein and provided with a movable bottom which is held open until an excess of gas is generated when it automatically closes, as and for the purpose set forth.

7. The combination of a water-tank, a generator movable therein, a self-closing bottom for said generator, and means for holding said bottom open when the generator is in its lowermost position, substantially as described. 55

8. The combination of the water-tank, the generator movable therein, a hinged bottom for said generator, adapted to be closed by gas-pressure, and a rod projecting from the bottom and adapted to collide with the bottom of the tank to open the said bottom. 60

9. The combination of a water-tank, a generator movable therein, a movable bottom for said generator, means for holding the bottom open when the generator is in its lowermost 65 position, and a stationary drain-pipe having its inlet adjacent to the said bottom, substantially as described.
